UNITED STATES PATENT OFFICE.

HENRY C. ADAMS, OF ALGONA, IOWA.

HAIR CRIMPER OR CURLER.

SPECIFICATION forming part of Letters Patent No. 788,987, dated May 2, 1905.

Application filed December 19, 1904. Serial No. 237,523.

To all whom it may concern:

Be it known that I, HENRY C. ADAMS, a citizen of the United States, residing at Algona, in the county of Kossuth and State of Iowa, have invented certain new and useful Improvements in Hair Crimpers or Curlers; and I do declare the following to be a full, clear, and exact description of the invention, such as will enable others skilled in the art to which it applies to make and use the same.

My invention relates to improvements in hair crimping and curling devices of that class in which a lock or strand of hair is wound or wrapped upon a suitable body and retained thereon a sufficient length of time to give the hair a curly or wavy appearance when released from such body.

The object of my invention is to provide a device of this character which will be simple in construction, durable in use, very efficient for the purpose intended, and comparatively inexpensive to manufacture.

With the above and other objects in view the invention consists of certain novel features of construction, combination, and arrangement of parts, as will be hereinafter described and claimed.

In the accompanying drawings, Figure 1 is a perspective view of my improved hair-crimper, showing the same in its opened position. Fig. 2 is a side elevation of the same in its closed position. Fig. 3 is an edge view of the same. Fig. 4 is a detail view, on an enlarged scale, of the outer or free end of the body portion of the device; and Fig. 5 is a similar view of the outer or free end of the spring-bail, showing the spring-jaws formed by the small supplemental loop upon the end of said bail.

Referring to the drawings by numeral, 1 denotes the body portion of my improved hair-crimper, upon which the hair is wound or wrapped, and 2 denotes a spring bail or loop, pivotally mounted upon said body portion and adapted to retain or clamp the hair thereon. While said body portion 1 is preferably made of bone, it will be understood that, if desired, it may be made of aluminium, celluloid, or any other metal, composition, or material.

As shown, this body portion is in the form of

a straight flat strip which tapers slightly toward one of its ends and is substantially rectangular in cross-section, its edges being slightly rounded, as shown. At the smaller end of the body portion upon both of its side faces are transversely and longitudinally extending grooves 3 and 4, the latter of which communicate at the end of said body portion and form a transversely-extending groove or recess 5 in said end. The grooves 3 form a transversely-extending head 6, which is divided in two parts or halves by the grooves 4 and 5.

The spring bail or loop 2 is preferably formed of a single piece of resilient metal rod or wire by bending the same upon itself at its center to form a loop or eye 7, a small supplemental loop 8, long side portions 9, and inwardly-extending portions 10, which terminate in eyes 11, through which and through the large end of the body portion 1 is passed a pivot-pin or rivet 12. The end loop 7 forms a finger-piece by means of which the bail 2 may be readily operated, and the small supplemental loop 8 is adapted to form two spring-jaws 13, which coat with the grooves 3 and 4 in the outer end of the body portion 1, the head 6 being adapted to enter the loop 8, as shown. It will be seen that when the free end of the bail 2 is forced upon the free end of the body portion 1 the spring-jaws 13 will enter the transversely-extending grooves 3 and the head 6 the loop 8. In doing this the spring-jaws 13 will be forced apart, since the head 6 is of greater size than the loop 8, so that when the said loop and the jaws 13 aline with the grooves 4 they will spring into the latter to retain the bail upon the body portion of the device.

In using the device a strand or lock of hair is wrapped around the body portion 1 when the parts are in the position shown in Fig. 1 of the drawings, and the bail 2 is then swung over the body portion to retain the hair thereon. It will be seen that when any considerable amount of hair is wrapped upon the body portion the side portions 9 of the bail will be forced outwardly and will cause said bail to shorten slightly, so that the neck of the loop 7 or the upper portion of the loop 8 will enter

the end groove 5; but since the jaws 13 and the loop 8 are normally seated in the grooves 4 when the device is in its closed position the bail will be securely retained upon the body 5 portion without the engagement of the neck of the same loop 7 with the groove 5.

Various changes in the form, proportion, and the minor details of construction may be resorted to without departing from the principle or sacrificing any of the advantages of this invention.

Having thus described my invention, what I claim as new, and desire to secure by Letters Patent, is—

15 A hair crimper or curler comprising a body portion provided upon both of its side faces, at one of its ends, with intersecting longitudinal

and transverse grooves and at said end with a notch which communicates with said longitudinal grooves, and a longitudinally-extensible 20 spring-bail pivotally mounted upon said body portion and formed at its free end with a loop which provides spring-jaws adapted to engage said intersecting grooves, said loop engaging said notch in the end of said body portion 25 when said bail shortens, substantially as described.

In testimony whereof I have hereunto set my hand in presence of two subscribing witnesses.

HENRY C. ADAMS.
